MIXING-MACHINE.

1,048,763.

Specification of Letters Patent. Patented Dec. 31, 1912.

Application filed March 30, 1908. Serial No. 424,015.

To all whom it may concern:

Be it known that I, RICHARD TIEDTKE, engineer, citizen of the Empire of Germany, and residing at Höchst-on-the-Main, Germany, have invented certain Improvements 5 in Mixing-Machines, of which the following is a specification.

This invention relates to improvements in mixing machines of the type in which there 10 are revolving guides, such as helical conveyers, for moving the materials to and fro, and while it is particularly well adapted for use in mixing colors, where a thorough mixture is essential, it is also useful for mixing other substances, particularly dry substances, such as gunpowder, etc.

According to the invention there are arranged in a suitable container mounted to revolve on a horizontal or substantially 20 horizontal axis, helical surfaces, or their equivalents, having a common axis, and the usual lifting plates, in such a manner that the materials to be mixed are subjected to the usual tumbling movement and are also 25 caused to travel in a closed path extending from end to end of the container, one of the conveyers moving the material in one direction, while the other, which may be situated within the first, returns the material in the 30 opposite direction.

For example, the materials may be conveyed from one end to the other of a suitable drum by a revolving helical blade and returned by revolving lifting plates so constructed that in letting fall again the material they have lifted they guide it in the opposite direction to that in which it is conveyed by the helical blade. Thus in addition to receiving the tumbling motion 40 usual in mixing machines the materials travel in a closed path parallel to the axis of the helical blade. This axis is horizontal or substantially so, and the elevating plates are preferably in rows along lines parallel 45 to the axis.

An important advantage of the invention is that dry powders, such as colors, etc., may be thoroughly mixed without causing dust.

Another advantage is that after mixing, the material may be discharged without 50 changing the direction of rotation of the mixing drum.

The accompanying drawings illustrate the invention, Figure 1 being a longitudinal section, Fig. 2 a cross section on line 2—2 of 55 Fig. 1, and Fig. 3 a detail view.

a is a drum mounted to rotate about its axis in a horizontal position. On its inner surface is fixed the helical blade or guide *b* and within the imaginary cylindrical surface circumscribed by the inner edge of the helical blade are suitably mounted lifting plates *c* parallel to the axis of the drum and, in cross section, radial to this axis. To these plates are fixed blades or guides *d* oblique 60 to the length of the plate so that the material which the plate lifts is caused to fall in the direction of the end *e* of the drum.

At the end *h* of the drum there is a stationary double spout *f* *f'* controlled by a 70 revolving guide *g*. When the latter is in the position shown in Fig. 3, the materials can be charged into the drum through spout *f*, whereas when the guide is in the position shown in Fig. 1 the mixed materials can be 75 discharged through spout *f'*.

As the materials are charged into the drum they are lifted by the plates *c* and caused to travel, while being tumbled, toward the end *e*; at the same time such portion of them as is not being tumbled travels toward the end *h*, being conveyed along the surface of the drum by the helix *b*. The helical blade terminates in chutes *i* fixed to the end *h* so that the material carried by the 80 helical blade is delivered through these chutes when it arrives at this end. So long as the guide *g* remains in the charging position (Fig. 3) the material delivered through the chutes *i* falls off the inclined surface *g'* 85 of the guide and is again tumbled and moved toward end *e* by plates *c*; that is to say the materials travel in a closed path indicated by arrows *y* (Fig. 1). When the guide *g* is turned into the discharging position (Fig. 1) the chutes *i* deliver into it 90 95

and the drum is gradually emptied through spout f'.

The usual cylindrical drum is preferred, but the invention is equally applicable to 5 conical drums. Since there is only one opening both for charging and discharging in one of the ends, the drum can be half filled with the materials, which is not possible in the case of the known conical drums 10 having automatic discharge, wherein the discharge openings are at the edge of the smaller end.

A particularly good intermixture can be obtained by a machine constructed according 15 to the invention, in that within the cylinder there are, in addition to the usual lifting plates, right and left hand helical surfaces or guide blades which determine the movement of the materials in a closed path 20 extending from end to end of the drum.

The mixing machine herein illustrated and described and heretofore claimed in this application is claimed in the divisional application hereof, Serial No. 589,440, filed 25 October 27th, 1910 for mixing machines.

Having now particularly described and ascertained the nature of my said invention and in what manner the same is to be performed, I declare that what I claim is:—

30 1. The combination with a drum, of a stationary feeding spout and a discharge spout at one end of the drum, a guide adapted to register with either of said spouts and connect the same with the interior of the 35 drum and when connected with the feeding spout to close the outlet against discharge of the material from the drum, and when connected with the discharge spout to receive these materials and discharge them, and 40 lifting means associated with the drum for discharging the materials upon said guide, substantially as described.

2. In a mixing machine, the combination of a horizontally-rotating mixing cylinder 45 provided with a feeding and discharge opening and means for closing the said opening, a series of guides for moving the material from end to end of said cylinder, and a series of radial lifting plates extending 50 longitudinally of the cylinder and disposed in a different radial zone from that occupied by said guides for tumbling the material to be mixed.

3. In a device of the character specified, 55 a revolving, horizontal drum provided with a combined feeding and discharging opening, means for closing said opening against the discharge of material, a helical guide within the drum for conveying material in 60 one direction, lifting plates for tumbling same, and guides for moving the material in the opposite direction, said guides and plates extending substantially from end

to end of the drum, substantially as described.

65

4. In a mixing machine, the combination of a rotatable mixing drum having a discharge opening, a delivery chute and a gate supported by the chute and arranged when adjusted to one position to set vertically 70 above the inner end of the delivery chute and closing it with one of its edges adjacent to the end wall of the drum above the discharge opening, and extending thence downward and inward, whereby it serves to divert material which is lifted back into the drum for further mixing and prevent it from entering the delivery chute.

75

5. In a mixing machine, the combination of a rotatable mixing drum having an axial 80 discharge opening a delivery chute extending through the said opening into the drum and formed with an outer stationary portion, and an adjustable portion located within the drum and pivoted to the stationary 85 part of the chute and arranged when in one position to form an extension of the chute within the drum and when adjusted to another position to form a cut-off for the chute and for the discharge opening, and 90 means for adjusting the said inner section of the chute.

95

6. In a mixing machine, the combination of a rotatable mixing drum having an axial discharge opening, a delivery chute extending 95 through the said opening into the drum and formed with an outer stationary portion, and an adjustable portion located within the drum and pivoted to the stationary 100 portion arranged when in one position to permit discharge through the discharge opening, and when adjusted to another position to form a cut-off within the drum for the chute and for the discharge opening, and 105 means for adjusting said adjustable portion of the chute.

100

7. In a mixing machine, the combination of a rotatable mixing drum having an axial discharge opening, a delivery chute extending 110 through the said opening into the drum and formed with an outer stationary portion, and an adjustable portion located within the drum and pivoted to the stationary portion axially of the drum arranged when in one position to permit discharge through 115 the discharge opening, and when adjusted to another position to form a cut-off within the drum for the chute and for the discharge opening, and means for adjusting said adjustable portion of the chute.

115

8. In a mixing machine, the combination of a rotatable mixing drum having a discharge opening, a delivery chute, and a gate pivotally supported by the chute and arranged when adjusted to one position to set 125 vertically above the inner end of the de-

120

livery chute and close it and with one of its edges adjacent to the end wall of the drum above the discharge opening and extending thence downward and inward whereby it
5 serves to divert material which is lifted back into the drum for further mixing and prevent it from entering the delivery chute.

In testimony that I claim the foregoing as my invention, I have signed my name in presence of two subscribing witnesses.

RICHARD TIEDTKE.
